US00D764124S

(12) **United States Design Patent**
Shinozaki

(10) **Patent No.:** **US D764,124 S**
(b4) **Date of Patent:** **** Aug. 16, 2016**

(54) **BRUSH FOR CLEANING SEMICONDUCTOR
POLISHING DISK**

(71) Applicant: **EBARA CORPORATION**, Tokyo (JP)

(72) Inventor: **Hiroyuki Shinozaki**, Tokyo (JP)

(73) Assignee: **EBARA CORPORATION**, Tokyo (JP)

(**) Term: **14 Years**

(21) Appl. No.: **29/445,125**

(22) Filed: **Feb. 7, 2013**

(30) **Foreign Application Priority Data**

Aug. 7, 2012 (JP) 2012-018893

(51) LOC (10) Cl. **15-05**

(52) U.S. Cl.

USPC **D32/25**

(58) **Field of Classification Search**

USPC D4/130, 119, 114, 136, 129, 100, 120,
D4/199; 15/143.1; D30/158; D24/119;
D25/113; D32/25

(57) **CLAIM**

The ornamental design for a brush for cleaning semiconductor polishing disk, as shown and described.

DESCRIPTION

FIG. 1 is a perspective view of a brush for cleaning semiconductor polishing disk showing my new design;

FIG. 2 is a top view thereof;

FIG. 3 is a front elevation view thereof;

FIG. 4 is a bottom plan view thereof;

FIG. 5 is a right side view thereof; and,

FIG. 6 is a reference view showing a usable state thereof. The broken line showing is included for the purpose of illustrating environment and forms no part of the claimed design.

1 Claim, 6 Drawing Sheets
